FORMING OF PAPERBOARDS

Ewen Ross Smith, London, England, assignor to
Papercrete Limited, London, EnglandApplication August 19, 1935, Serial No. 36,925
In Great Britain August 20, 1934

3 Claims. (Cl. 92—61)

This invention relates to the forming of paper boards or plates of relatively considerable thickness and has for its object to devise a simple and efficient method and apparatus by which 5 such boards may be readily and cheaply made of any desired thickness.

The invention consists in a method of forming paper board from paper pulp which comprises sucking a layer of pulp from stuff water on to a 10 sieve and couching the formed layer on to a flexible body by which such layer is also removed from the sieve to permit of the formation of a further layer thereon.

The invention also consists in apparatus for 15 forming paper board by the method according to the preceding paragraph comprising a platen having thereon a sieve spaced apart from the platen so that a layer of pulp may be deposited thereon by suction and a second platen having 20 a surface formed by a flexible body and controlled by hydraulic ram and cylinder or otherwise, so that the flexible body may be moved into contact with the formed layer on the sieve to couch the same and remove it from the sieve preparatory 25 to the formation of a further layer thereon.

Further features of the invention will be apparent from the description given hereafter.

The accompanying drawing illustrates in sectional elevation one convenient form of apparatus 30 in accordance with the invention.

In carrying my invention into effect in one convenient manner, I may form my improved apparatus with any suitable bedplate *a* foundation or supporting framework, upon pillars *b* or 35 slides forming part of which I mount upper and lower platens, either or both of which may be movable for the purpose of causing the same to approach or recede from one another as may be necessary during the operation of forming paper 40 boards.

In the particular construction shown, the upper platen may carry or comprise a flanged ring *c* of any desired shape in plan within which I 45 mount a metal or other backing or support *d* spaced slightly apart from which is a sieve plate *e* and co-operating with this upper fixed platen I arrange a lower movable platen *f* adapted to be controlled by hydraulic ram and cylinder of 50 suitable form so that it may be made to approach or recede from the upper platen.

The lower platen *f* is preferably formed with a peripheral annulus *f'* into which the stuff water is admitted for suction through the upper 55 sieve so as to deposit thereon a layer of felted

fibrous material, the thickness of which is obviously limited by the capacity of the layer to pass further liquid therethrough.

Within the part of the lower platen surrounded by the above annulus, I arrange a metal or other plate *g* having a rubber or rubber and felt or other like flexible surface *h* constituting a flexible body adapted to be pressed into contact with the sieve by operation of the hydraulic ram so as to couch the layer of pulp upon the sieve and remove 10 the same on reverse movement of the hydraulic ram so that such layer *i* is thus transferred from the sieve to the flexible body whereupon a further layer may be deposited upon the sieve and subsequently couched upon the flexible body and so on 15 until a board or plate of the desired thickness has thus been transferred to the flexible body.

Behind the backing plate of this flexible body I dispose an inflatable bag or series of bags *k* arranged in recesses or otherwise located so that 20 during normal operation of the hydraulic ram the bag or bags will not be compressed and the couching pressure is that which is thus due to the hydraulic pressure and which will be determined by the relative areas of the sieve and hydraulic cylinder respectively. 25

When, however, the last layer has been formed upon the sieve, the ram is moved so that the layers upon the flexible body are brought into contact with the layer upon the sieve and the platens 30 locked in position by suitable means (such as the pivoted locking members *l*), whereupon high pressure water or air is admitted to the inflatable bag or bags and the pressure is maintained for sufficient time to consolidate the material and 35 the layers together and to express as much as possible of the remaining water therefrom.

When the board or plate is sufficiently pressed, the pressure is released, the head unlocked and the platens separated to permit of removal of the 40 finished board.

By the invention, I am able to produce plain paper boards of any desired thickness or by suitable shaping of the parts the boards may be embossed or corrugated or otherwise similarly 45 formed.

By a suitable construction of machine I may form any number of the boards simultaneously.

It will be understood that the apparatus is provided with all necessary valves and regulating 50 means, the operations of which may be timed and controlled in proper sequence by hand or automatically as for example in the manner described in the specification of application Serial No. 723,774 or in any other suitable manner.

Having now described my invention, what I claim as new and desire to secure by Letters Patent is:—

1. Apparatus for forming paper board by the paper making process comprising two platens movable relatively to one another and enclosing a space to which stuff water is admitted, a sieve carried by one of the platens on to which a layer of pulp is deposited by suction, and a member carried by the other platen and having a flexible surface adapted to be pressed into contact with the sieve to couch the layer of pulp thereon and transfer the same from the sieve to the flexible surface preparatory to the formation of a further pulp layer upon the sieve.

2. Apparatus for forming paper board by the paper making process having the combination of claim 1 and means for locking the platens together when the board reaches the desired thickness and means for applying high pressure to consolidate the board.

3. Apparatus for forming paper board by the paper-making process according to claim 1 characterized by the member having a flexible surface being movable in relation to the platen carrying the same and combined with inflatable means arranged to apply high pressure to said movable member for the purpose of consolidating the board.

EWEN ROSS SMITH. 15
